PETER P. VALBOE, OF DETROIT, MICHIGAN, ASSIGNOR TO PENBERTHY INJECTOR CO., OF DETROIT, MICHIGAN, A CORPORATION OF MICHIGAN.

EXPLOSION-ENGINE OILER.

1,144,572.

Specification of Letters Patent. Patented June 29, 1915.

Application filed January 29, 1914. Serial No. 815,252.

To all whom it may concern:

Be it known that I, PETER P. VALBOE, a citizen of the United States, residing at Detroit, in the county of Wayne and State of Michigan, have invented a new and useful 5 Explosion-Engine Oiler, of which the following is a specification.

This invention has reference to improvements in oilers particularly for explosion engines, but which may be used wherever there 10 is a liability of regurgitation of the lubricant.

It is customary to provide oilers with sight feeds and it has been proposed to introduce a 15 valve between the engine and the sight feed in order that on the compression stroke, and also on the power stroke of the engine, the gases shall be prevented from finding their way into the sight feed chamber, carrying 20 some of the lubricant already fed from the sight feed chamber back thereinto, while the explosion destroys the formed drops, thus obscuring the sight openings both by the lubricant and by particles of carbon which 25 might be forced into the sight chamber with the gases of the charge or the gases of combustion. For one reason or another such valve arrangements have proven inefficient and obscuring of the glass walls of the sight 30 feed chamber frequently occurs.

With the present invention a valve is provided between the sight feed chamber and the explosion chamber of the engine, but the arrangement is such that the valve positively 35 and firmly closes before any sensible amount of the gases can find their way by the valve and into the sight feed chamber, while on the suction stroke of the engine the valve at once moves to the full open position permitting 40 the movement of the lubricant through the valve and to the moving parts of the engine both by gravity and by suction. Experience has shown that the glass walls of the sight feed chamber remain clear and unob- 45 scured for indefinitely long periods of time without any interference with the passage of the lubricant in sufficient quantities to the moving parts of the engine. This is due to the structure and arrangement of the 50 valve mechanism, whereby the valve is seated in the closed position more rapidly than even the gases of explosion can find their way about the valve to the sight chamber.

The invention will be best understood 55 from a consideration of the following de-

tailed description, taken in connection with the accompanying drawings forming part of this specification, with the further understanding that while the drawings show a practical form of the invention, the latter is 60 not confined to any strict conformity with the showing of the drawings, but may be changed and modified so long as such changes and modifications mark no material departure from the salient features of the 65 invention.

In the drawings:—Figure 1 is a longitudinal diametric section of the sight feed end of an oiler structure, the drawing being on an enlarged scale. Fig. 2 is a plan view of 70 an adjustable limiting member for the valve, the view being taken from that end through which the lubricant enters to pass to the engine. Fig. 3 is a plan view of the valve as seen from the end toward the sight chamber 75 of the oiler. Fig. 4 is a fragmentary sectional view of the valve portion of the structure shown in Fig. 1, showing the valve in the position assumed when subjected to back pressure from the engine. 80

Referring to the drawings there is shown the nozzle end of an oiler 1, the showing including a nozzle 2 through which the oil, which name applies to any suitable lubricant, finds its way after passing the usual 85 controlling valve not shown in the drawings. The nozzle 2 discharges into a chamber 3 enclosed by a tube 4 of glass lodged in a neck 5 which may be integral with the body of the oiler 1 and axial to the nozzle 2, and this 90 neck is provided with diametrically opposite sight openings 6 through which the glass tube 4 is visible, these sight openings being arranged to give a view of a drop of oil issuing from the nozzle 2. The end of the 95 neck 5 remote from the body 1 of the oiler is screw threaded for the reception of a cap 7, which latter terminates at the end remote from the neck 5 in a neck 8 of less diameter than the neck 5, and this neck 8 is externally 100 threaded for insertion in the wall of the engine cylinder or wherever the oiler is installed. The glass tube 4 at the end adjacent to the nozzle 2 is lodged against a gasket 9 and at the end adjacent to the cap 7 is 105 lodged against another gasket 10 held in place by the cap 7, and between this gasket 10 and the cap 7 there is lodged a disk 11 of fine wire gauze or other suitable screen material. It is customary to make the gaskets 110

9 and 10 of cork, but any other suitable material may be employed. The interior of the neck 8 is formed with an axial chamber 12 opening at that end of the neck designed to enter the engine cylinder or other structure, and this chamber at the inner end terminates in an annular seat 13 from which there is extended an axial passage 14 of less diameter than the chamber 12, and opening into an expanding portion 15 of the interior of the cap 7 covered by the screen 11. The open end of the chamber 7 has its walls interiorly screw threaded, as shown at 16, for the reception of a hollow nut 17 freely open at one end and there provided with diametrically opposite recesses 18 for the application of a manipulating tool, while at the other end the hollow nut is closed except for an axial passage 19 extending through an axial stud or boss 20 on the side of the corresponding end of the nut remote from the end provided with the recesses 18. The boss 20 has side openings 21 communicating with the passage 19.

25 Lodged in the chamber 12 is a valve 22 having a hollow stem 23 adapted to the passage 14 and terminating within the chamber 12 in a radially expanded head 24 of a size to extend beyond the seat 13. The hollow stem 22 has a passage 25 lengthwise therethrough from the end remote from the head 24 to said head, but not through it, while through the side wall of the stem 23 is an opening 26 communicating with the interior or bore 22 of the stem 23. The valve 22 is free to slide lengthwise in the bore 14 between the seat 13 and the adjacent end of the boss 20 and the distance between the boss 20 and the seat 13 determines the play of the valve, and as it is customary to install the oiler in an upright position the valve will normally gravitate to the boss 20 upon which it ordinarily rests, and in which position the passage 26 is freely open to the chamber 12, while the passage 25 is always open to the interior of the sight chamber 3, but separated therefrom by the screen 11.

When the oiler is installed on an explosion engine, say, on the cylinder of the engine, so as to deliver lubricating oil to the piston of the engine, it may be subjected to the suction of the engine and to the action of the pressure of the charge during the compression stroke of the engine and the pressure of the burnt gases of combustion during the power stroke of the engine. When there is neither suction nor compression the valve 22 falls to and rests upon the boss 17, which latter is employed as an adjustable stop member for the valve in its movement away from the valve seat 13. Suppose, now, that the piston is moving on the suction stroke. The valve then remains in

contact with the limiting stop or boss 20. The lubricating oil flows through the nozzle 2 into the chamber 3, so that it will drop upon the screen 11 and from thence into the space 15 below the screen, and finally 70 into the passage 14 and through the valve by way of the passage 26 into the chamber 12, ultimately finding its way through the openings 21 into the passage 19 and so to the engine piston. Upon the return 75 stroke of the piston compressed gases are forced through the passage 19 into the chamber 12, but in so flowing they strike upon the expanded head 24 of the valve, which expanded head projects radially beyond 80 the valve seat 13, and since the head may be in the form of a disk of substantially equal thickness with parallel plane faces, the stream of compressed gas striking the broad face of the valve head presented 85 toward the passage 19 quickly forces the valve toward the seat 13 until the latter is engaged by the valve, the passage 26 in the meantime moving up into the passage 14 and communication between the chamber 90 12 and the passage 26 is at once cut off even before any of the diverted stream of gases reaches it, the disk-like valve head serving as a baffle plate. The valve may be actually very light in weight and the stream of 95 gases may readily expand into the chamber 12, so that their flow is reduced to an extent preventing them from reaching the bore 25 of the valve stem to any noticeable extent. The increasing pressure within the chamber 100 12 caused by the advancing compression stroke holds the valve firmly to its seat, wherefore the gases are held back from access to the sight chamber, wherefore there is then no flow of lubricant into the sight 105 chamber from the nozzle 2 and no flow of gas into the sight chamber, nor is there re-gurgitation of oil into the sight chamber. The same operation occurs when there is an explosion in the explosion chamber of 110 the engine resulting in the power stroke thereof, in which case were it not for the presence of the valve 22 some of the gases of combustion would find their way into the sight chamber and carry more or less 115 carbon with them, which mixing with oil in the sight chamber very soon obscures the glass walls and makes it difficult to observe the dropping of the oil from the nozzle 2 through the then obscured sight openings. This difficulty is avoided by the present invention as has been found by actual 120 use, and it would seem that the valve moves so quickly under the stream of gas under pressure that it closes before any sensible 125 amount of gas is projected into the sight chamber, for long continued use has failed to show any obscuring deposit upon the glass walls of the sight chamber where opposite the sight openings 6 under circum- 130

stances which will produce obscuring of the glass opposite the sight openings with valved structures as heretofore produced.

The hollow nut 17 provides a ready means for adjusting the throw of the valve to suit different conditions and to aid in obtaining the best results under different working conditions. The boss 20 does not interfere in any way with the free flow of oil after having passed the valve, since the passages 21 permit the oil to readily find its way to the passage 19 and from thence to the interior of the hollow nut and so to the engine piston.

As in all oilers of this kind the valve and valve passages are relatively small, and hence may become easily choked by minute particles often found in lubricating oil, wherefore the screen or strainer 11 is provided, this also aiding in arresting the access of any small particles which might possibly pass the valve to the sight chamber. The screen 11 offers no material impediment to the flow of lubricating oil, and while its presence is advantageous in holding back any particles which might choke or obscure passages or sight openings, it is not at all obstructive as to the free flow of the lubricant from the nozzle 2 to and through the valve.

30 What is claimed is:—

1. An oiler for explosion engines provided with a sight feed chamber, and another chamber between the sight feed chamber and the discharge end of the oiler, a valve within the second-named chamber mounted to have unimpeded movement to the open and closed positions and provided with a laterally expanded baffle face toward the outlet end of the oiler, and means for directing a constricted stream of gases of explosion against the central portion of the baffle face, whereby the gases of explosion seat the valve before such gases can reach the sight feed chamber.

45 2. An oiler for explosion engines provided with a sight feed chamber and another chamber between the sight feed chamber and the discharge end of the oiler, a freely reciprocable valve within the second chamber, having a laterally expanded disk-like head presented toward the discharge end of the oiler, and said oiler having a valve seat at that end of the second-named chamber toward the sight feed chamber with the valve seat of less diameter than the face of the head of the valve presented theretoward, and means for directing a stream of gases of explosion against the central portion of the laterally expanded valve head to cause seating of the valve before the gases can reach the sight feed chamber.

3. An oiler for explosion engines provided with a sight feed chamber and another chamber between the sight feed chamber and the discharge end of the oiler, a freely recip-

rocable valve within the second-named chamber, said valve having a laterally expanded disk-like head within the chamber, and a stem with a longitudinal bore entering it from the end remote from the valve head 70 and provided with a passage leading from the bore through the stem adjacent to the valve head, and means for directing a constricted stream of gases of explosion against the central portion of that face of the valve 75 head toward the discharge end of the oiler.

4. An oiler for explosion engines provided with a sight feed chamber and a passage leading therefrom to the discharge end of the oiler, said passage being of relatively 80 contracted diameter where leaving the sight feed chamber, and then continuing as a laterally expanded chamber having the outlet end internally screw threaded and where joining the passage of smaller diameter being shaped into a valve seat, a valve with a laterally expanded disk-like head having an axially extended hollow stem on one side adapted to the passage of smaller diameter leading from the sight feed chamber and 85 said stem having a side outlet adjacent to the head, and a hollow plug or nut adapted to the screw threaded end of the portion of the passage leading from the sight feed chamber, said plug having one end partially 90 closed and provided with a centrally located passage therethrough and a central boss through which the passage extends and which boss is provided with side outlets communicating with such central passage. 100

5. An oiler for explosion engines provided with a sight feed chamber, and a passage leading therefrom to the discharge end of the oiler, said passage being of relatively contracted diameter where leaving the sight 105 feed chamber, and then continuing as a laterally expanded chamber having the outlet end internally screw threaded and where joining the passage of smaller diameter being shaped into a valve seat, a valve with a laterally expanded disk-like head having an axially extended hollow stem on one side adapted to the passage of smaller diameter leading from the sight feed chamber, and 110 said stem having a side outlet adjacent to the head, and a hollow plug or nut adapted to the screw threaded end of the portion of the passage leading from the sight feed chamber, said plug having one end partially closed and provided with a centrally located 115 passage therethrough and a central boss through which the passage extends and which boss is provided with side outlets communicating with such central passage, the sight feed chamber adjacent to the outlet passage therefrom being provided with a screen pervious to lubricant and resistant to 120 obscuring particles.

6. An oiler provided with a sight feed chamber having a passage leading there- 125

from to the discharge end of the oiler, said passage including another chamber with a valve seat at the end of the portion of the passage leading from the sight feed chamber to the second chamber and the portion of the passage leading from the second chamber to the discharge end of the oiler being of less lateral extent than said second chamber where communicating with it, and 5 a valve in the second chamber reciprocable therein in the direction of the length of the outlet passage of the oiler and adapted to the said valve seat, the valve having the face toward the outlet end of the second 10 chamber expanded into a baffle surface and said outlet end of the second chamber being located with respect to the baffle face of the valve to cause a stream of gas entering the second chamber from the outlet end of the 15 oiler to strike against the central portion of the valve and from thence spread laterally into the chamber to seat the valve in closing relation to the inlet end of the second chamber before said gas stream reaches said inlet 20 end.

7. An oiler for explosion engines provided with a sight feed chamber and another chamber between the sight feed chamber and the discharge end of the oiler and in communication with the sight feed chamber, that 25 end of the second-named chamber remote from the sight feed chamber comprising an adjustable member having an axially extended boss of less diameter than said adjustable member or second-named chamber and provided with a centralized constricted 30 passage opening into said second-named chamber, and a valve lodged in the second-named chamber and provided with a laterally expanded head of greater diameter than the external diameter of the boss, said 35 valve being freely reciprocable in the second-named chamber and normally seated on the boss.

8. An oiler for explosion engines provided with a sight feed chamber having an outlet passage expanded intermediately into a laterally extended chamber, and a freely reciprocable valve within the chamber 40 provided with a laterally expanded disk-shaped head movable into and out of closing relation to the part of the passage connecting the two chambers, the disk-shaped head of the valve being of greater lateral extent 45 than the diameter of the part of the passage connecting the two chambers and that portion of the passage leading away from the second-named chamber being of less diameter than the valve head and located with respect thereto to direct streams of fluid 50 entering the outlet end of the oiler toward the

said chambers against a centralized portion of the disk-shaped head to be in turn directed by said head toward the margins thereof, whereby the valve is moved to position to close communication between the two chambers before the impelling fluid can find access to the first-named chamber. 55

9. An oiler for explosion engines having an outlet passage with an intermediately located and laterally expanded chamber, and a freely reciprocable valve in the chamber having a laterally expanded head presenting a baffle face toward the outlet end of such chamber, and said outlet end of the 70 chamber being located substantially in line with the longitudinal axis of movement of the valve to direct streams of gas reaching the chamber from the outlet end of the oiler against a restricted centralized zone of the 75 head to be diverted therefrom toward the sides of the chamber away from the inlet end of said chamber, whereby such streams of gas move the valve to position to close the 80 inlet end of the chamber before it is reached 85 by the gas.

10. An oiler for explosion engines having a sight feed chamber with a taper bottom and an outlet passage leading from said taper bottom to the outlet end of the oiler, 90 said passage including a laterally expanded chamber intermediate of its length with an adjustable hollow plug forming that end of the intermediate chamber remote from the sight feed chamber and said plug having a 95 central axial boss entering the second chamber, and said boss having a passage through it, a valve having a disk-like head within the second chamber and a stem extending into that portion of the passage connecting the 100 two chambers, the valve having its head laterally expanded to a greater extent than the outside diameter of the boss, and said boss and valve head being so constructed and arranged that a stream of gas directed through 105 the outlet end of the oiler toward the valve will strike the latter at an intermediate portion and be diverted thereby toward the sides of the intermediate chamber to force the valve into closing relation to the entering passage of said second chamber before the actuating gas can reach the sight feed chamber, and a fine gauze screen extended across the wide end of the tapered bottom portion of the sight feed chamber. 110

In testimony that I claim the foregoing as my own, I have hereto affixed my signature in the presence of two witnesses.

PETER P. VALBOE.
